UNITED STATES PATENT OFFICE.

JOHN R. BLAKESLEE, OF CLEVELAND, OHIO, ASSIGNOR TO THE AJAX MANUFACTURING COMPANY, OF CLEVELAND, OHIO, A CORPORATION OF OHIO.

BOLT-HEADING MACHINE.

1,111,720.

Specification of Letters Patent. Patented Sept. 29, 1914.

Application filed October 18, 1911. Serial No. 655,372.

To all whom it may concern:

Be it known that I, JOHN R. BLAKESLEE, a citizen of the United States, and a resident of Cleveland, county of Cuyahoga, and 5 State of Ohio, have invented a new and useful Improvement in Bolt-Heading Machines, of which the following is a specification, the principle of the invention being herein explained and the best mode in which I have contemplated applying that principle, so as to distinguish it from other inventions.

In the operation of heading dies, in which the forming die and upsetting die, proper, 15 are independently movable, so as to permit such forming die to be advanced into position to inclose the stock that is to be upset prior to the advance of the upsetting die, more or less difficulty is experienced in dis- 20 engaging the freshly formed head from the die. In machines of this class, it will be understood that ordinarily a section of stock of sufficient length to form the particular bolt, or other article being manufactured, is 25 cut off from the rod or bar before the head is formed in the fashion just described. Accordingly, when the header slide is retracted, the head of the bolt will tend to stick in the die and be carried with it, thus interfering 30 with the formation of the next successive bolt, as should be obvious.

The object of the present invention is to so construct two-part forming dies, of the type referred to, as to eliminate the difficulty in 35 question, and to the accomplishment of this and related ends, said invention consists of the means hereinafter fully described and particularly pointed out in the claims.

The annexed drawings and the following 40 description set forth in detail certain mechanism embodying the invention, such disclosed means constituting, however, but one of various mechanical forms in which the principle of the invention may be used.

45 In said annexed drawings:—Figure 1 is a broken plan view of a forging, or upsetting, machine embodying my present improvements; Fig. 2 is a central vertical section of said machine showing the parts in the same 50 position as in Fig. 1; while Figs. 3, 4 and 5 are similar cross sectional views but showing the parts in operative positions respectively differing from each other and from that shown in Fig. 2.

Most of the details of the construction of

the machine frame 1 have been omitted from the foregoing figures as inessential, as also the driving connections for the crank shaft 2 which is mounted on said frame in the usual fashion. At the farther end of the 60 frame from said shaft, is located the feed opening 3 through which the stock is adapted to be fed between the gripping dies 4 and 5, the latter of which is movable relatively to the other to cut off the portion of the 65 stock that protrudes through the feed plate 6. Such cut-off section of stock is then finally gripped between said movable die 5 and the one 4 that remains stationary, so as to be held in line with the head forming 70 mechanism. This mechanism, which is of present interest, is designed to be operated by the crank shaft 2 and comprises in the first place, a slide corresponding with the ordinary header slide or machine of this 75 class, but made up of two parts 7 and 8. Of the parts of the slide, the first one is adapted to be reciprocated by means of cams 9 and 10 of which two pairs are provided, one pair 10 being arranged to advance said slide and 80 retain the same for a predetermined period of time in advanced position, while the other pair 9 co-acting with opposed faces on rearward extensions 11, 11 of the slide, is adapted to retract the slide. The other slide part 85 8, which is mounted on the main slide 7, preferably in a central longitudinally extending recess 12 in such slide, is reciprocated by the crank shaft 2 through a connecting rod 13 of the usual construction. 90

From the foregoing description of the operative connections between the slide parts and the shaft, it will be seen that a regular reciprocatory movement is imparted to the inner smaller slide part, while the larger 95 slide part, which incidentally supports said smaller part, is advanced and held in advanced position and then retracted, quite independently of the movement of the smaller slide, (so as to move faster and also be retracted farther than the latter) although the movements of the two slides are synchronized, as will be presently explained.

Secured to the forward end of the small slide part by a suitable clamp collar 14 and set bolt 15, is an extension 16 preferably cylindrical in form, that is of reduced diameter at its outer end, and furthermore formed with an annular recess just back of such end, so as to provide an undercut head 17. This 110

extension projects through an opening in the forward end of the larger slide and into a split sleeve 18 that is secured to such larger slide's forward end by a removable cap plate 5. 19. Sleeve 18 is formed with an enlargement 20 at its forward end that forms a holder adapted to receive a forming die 21, such die being secured therein by means of a set bolt 22, and being thus readily exchangeable with others of different size bore. The bore in such die, it will be understood, is of the form and size which it is desired to give to the bolt head in a transverse plane. There is also supported in the sleeve 18, an upsetting or heading tool 23, the forward end of the latter extending into the bore of forming die 21, while its rear end has a recessed or undercut head 24 similar to the head at the forward end of the extension 16. The 29 tool is secured to the header extension by means of a split collar 25 having an internal circular recess, that, when the two portions of the sleeve are drawn together, fits snugly around the juxtaposed undercut heads in question and thus locks the parts together.

Having thus described, with what is believed to be sufficient particularity, the construction of my improved machine, its general mode of operation may now be set forth. As has already been indicated, the stock, in the form of a rod or bar, is suitably fed through the feed opening 3 and between the gripping dies 4 and 5, so as to have the proper length of material project beyond said dies, as shown, for example, in Figs. 1 and 2. Thereupon the movable gripping die is caused to cut off such projecting portion of the stock and firmly press the same against the fixed die. Incidentally to the foregoing, the advance movement of the main header slide 7 begins, by reason of the engagement of cams 9 with the corresponding faces on said slide. At this stage, the inner slide 8 is in its completely retracted position, and while its advance begins simultaneously with the forward movement of the larger slide part, its movement is slower, so that such larger part with the sleeve and forming die carried at its forward end is advanced into the position shown in Fig. 3, before the inner slide with the extension thereof which carries the upsetting tool, has been advanced to bring the latter into contact with the stock. The cams, however, which advance the larger slide retain the latter in such position until the inner slide with the heading tool, catches up, as it were, the result of this being the upsetting of the portion of the stock that is inclosed within the forming die, as shown in Fig. 4. The return movement of the slide parts now begins, but here again the movement of the outer, larger slide part is more rapid than that of the inner slide, so that as a result, the sleeve and forming die are drawn back

more rapidly, as well as farther, than the extension which carries the upsetting tool. Such upsetting tool, accordingly, is left projecting as shown in Fig. 5, and as a result it will be obvious that the bolt head is forced or pushed out of the forming die, so that the bolt is left free to drop, and any tendency which it might have to stick in the forming die is eliminated.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the class described, the combination with means for gripping the stock; of a forming die; an upsetting tool reciprocable within said forming die; and means adapted to positively reciprocate said die and tool both relatively to the stock and independently of each other, said means being arranged to retract said forming die farther than said upsetting tool.

2. In mechanism of the class described, the combination with means for gripping the stock; of two independently reciprocable slides; a forming die carried by one of said slides; an upsetting tool carried by the other of said slides, said upsetting tool being reciprocable within said forming die; and means adapted to reciprocate said slides both relatively to the stock and independently of each other, said means being arranged to retract said first-named slide farther than said last-named slide.

3. In mechanism of the class described, the combination with means for gripping the stock; of two independently reciprocable slides; a forming die carried by one of said slides; an upsetting tool carried by the other of said slides, said upsetting tool being reciprocable within said forming die; cams adapted to reciprocate said first-named slide; and a crank connected to reciprocate said last-named slide, said cams being arranged to advance and retract the slide operated thereby more rapidly than said crank operated slide, and also to retract its slide farther than said crank-operated slide.

4. In mechanism of the class described, the combination with means for gripping the stock; of a main slide; a second slide carried by said main slide and reciprocable thereon in the direction of reciprocation of said main slide; a forming die carried by said main slide at its forward end; an upsetting tool carried by said second slide and extending within said forming die; a crank-shaft having its crank connected to regularly reciprocate said second slide; and cams on said shaft adapted to intermittently

reciprocate said main slide, said cams being arranged to advance said forming die more rapidly than said upsetting tool, retain the same in advanced position, and 5 then retract said forming die more rapidly, and also farther, than said upsetting tool.

5. In mechanism of the class described, the combination with means for gripping the stock; of a forming die; an upsetting tool 10 reciprocable within said forming die; and means for positively reciprocating said die and tool independently of each other, said means being arranged to advance the forming die faster than and beyond the upsetting tool, to retain the forming die in advanced position and simultaneously to advance the upsetting tool to the stock, and then simultaneously to retract the tool and 15 to retract the forming die faster than and beyond the upsetting tool.

6. In mechanism of the class described, the combination with means for gripping

the stock; of two independently reciprocable slides; a forming die carried by one of said slides; an upsetting tool carried by the other 25 of said slides, said upsetting tool being reciprocable within the forming die; cams adapted to reciprocate the first slide; and a crank connected to reciprocate the second slide, said cams and crank being arranged to reciprocate their respective slides so as 30 to advance the forming die faster than and beyond the upsetting tool, to retain the forming die in advanced position and simultaneously to advance the upsetting tool to 35 the stock, and then simultaneously to retract the tool and to retract the forming die faster than and beyond the upsetting tool.

Signed by me this 16th day of October, 1911.

JOHN R. BLAKESLEE.
